UNITED STATES PATENT OFFICE.

HOWARD L. KRATZ, OF PHILADELPHIA, PENNSYLVANIA, ASSIGNOR TO JOHN WANAMAKER PHILADELPHIA, OF PHILADELPHIA, PENNSYLVANIA, A CORPORATION OF PENNSYLVANIA.

DESIGN FOR A FOLDING SCREEN FOR A ROOM.

Application filed July 23, 1927. Serial No. 22,855. Term of patent 3½ years.

To all whom it may concern:

Be it known that I, HOWARD L. KRATZ, a citizen of the United States, residing in Philadelphia, Pennsylvania, have invented a certain new, original, and ornamental Design for a Folding Screen for a room, of which the following is a specification, reference being had to the accompanying drawing, in which—

Figure 1 is a perspective view of a folding screen for a room illustrating my new de-

sign only two sections of which are shown ornamented, it being understood that the ornamentation is continued on the two sections shown plain; and

Fig. 2 is a perspective view of one section of a screen on an enlarged scale.

I claim:—

The ornamental design for a folding screen for a room, substantially as shown and described.

HOWARD L. KRATZ.
